UNITED STATES PATENT OFFICE

2,470,444

GLASS CUTTER

George A. Philippe, Fort Smith, Ark.

Application February 21, 1946, Serial No. 649,170

6 Claims. (Cl. 49—52)

1

The invention relates to glass cutters, particularly the manually operated type, and has for its object to provide a device of this kind adapted for making relatively long cutting strokes against a straight edge, and constructed in a manner whereby the diamond carrying carriage will maintain its relative position against the straight edge for a cutting operation, irrespective of the position of the handle.

A further object is to rockably mount the cutter carriage in a yoke member in the plane of the handle, and to provide the yoke member with an upwardly extending shaft, rotatably mounted in a bearing of the handle head and to provide, within the handle head, spring means cooperating with the yoke shaft for normally returning the yoke to a position in the plane of the axis of the handle, and at the same time allowing lateral misalignment of the handle in relation to the yoke during the cutting operation.

A further object is to provide means whereby the spring means cooperating with the yoke shaft can be adjusted for adjusting the yoke into the plane of the axis of the handle.

A further object is to mount the diamond carrying carriage on trunnions within the yoke, thereby allowing side tilting of the yoke as well as angular positioning of the handle in relation to the yoke during the cutting operation.

A further object is to hingeably mount the handle member on the handle head, and to provide means whereby the handle may be locked in various angular positions in a vertical plane in relation to the head.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawings:

Figure 1 is a vertical longitudinal sectional view through the glass cutter.

Figure 2 is a top elevation.

Figure 3 is a top elevation of the glass cutter, showing the handle at an angle to the yoke and carriage, and the carriage against a straight edge.

Figure 4 is a transverse sectional view taken on line 4—4 of Figure 5.

Figure 5 is a perspective view of the diamond carrying carriage.

2

Figure 6 is a horizontal sectional view taken on line 6—6 of Figure 1.

Figure 7 is a perspective view of the handle head, parts being broken away to better show the structure.

The device is particularly adapted for cutting large sheets of glass, where the handle 1 is necessarily long and therefore the operator can not pull in a straight line, particularly when the operator has to reach over the table a great distance, and also as the tool approaches the end of its cut, and the tool is designed so the cutting carriage will remain against the straight edge 2, no matter whether the pull is absolutely a straight one or not. The handle 1 is hingeably connected at 3 by a bifurcated member 4 to the handle head 5, and threaded through the bifurcated portion 4 is a threaded shaft 6, which, when threaded inwardly, engages the eye 7 of the head and holds the handle at a predetermined upward angle in relation to the cutting tool. The head 5 is provided with a chamber 8 having spaced anti-frictional bearings 9 therein, and rotatably mounted in said bearings is the vertical yoke shaft 10. Yoke shaft 10 is provided with a kerf 11, in its upper end, which kerf receives the portion 12 of a coiled torsion spring 13. The other end of said spring is anchored at 14 in one of the slots 15 of a rotary adjustable sleeve 16, which sleeve is provided with an outwardly extended headed screw 17, extending through the slot 18 in one side of the head. By providing the screw 17, the sleeve 16 can be rotatably adjusted for varying the tension of the spring 13 and maintains the yoke shaft 10 in any desired rotatable position, and the yoke 19 in the plane of the axis of the handle. In other words, after a cutting operation, the yoke will immediately assume a position in the plane of the axis of the handle. By providing the additional anchoring slots for the spring additional tension adjusting means is provided in connection with the adjusting screw 17.

The lower ends of the arms 20 of the yoke 19 are provided with trunnion screws 21, and on which trunnion screws the diamond ferrule carrying carriage 22 is rockably mounted transversely in relation to the yoke 19. One of the trunnion screws 21 engages in a recess or bearing 23 of the transverse portion 24 of the turpentine cylinder 25, and the portion 24 is rigidly held in adjusted position by a screw 26. Extending transversely of the carriage 22 is a rotatably adjustable plug 27 having mounted in a transverse aperture through the plug the diamond ferrule 28, and the diamond ferrule is held in adjusted posi-

tion by a set screw 29, extending into the plug 27, and the plug is in turn held in adjusted position by a lock nut 30. It will be seen that the diamond ferrule may be adjusted to proper angle as well as the turpentine cylinder 25, having a swab 31 for depositing turpentine on the glass in advance of the diamond 32.

Referring to Figure 3 it will be seen that the handle 1 can assume an angular position to the straight edge, and at the same time the side of the carriage 22 will remain in engagement with the straight edge, and the yoke can oscillate from side to side on the trunnions 21 without affecting the position and engagement of the side of the carriage with the straight edge, hence it will be seen that the accurate cutting is not affected by the variations of angular pull by the operator on the handle 1, and that accurate cutting is obtained at all times.

The invention having been set forth what is claimed as new and useful is:

1. A glass cutter comprising a handle member, a head to which said handle member is connected, a cutter carriage yoke below said head, a vertical shaft carried by the upper portion of said yoke and rotatably mounted in the head, yieldable means for urging said yoke towards the plane of the axis of the handle, and a cutter carrying carriage rockably mounted within the yoke on pivotal points in the plane of the yoke.

2. A device as set forth in claim 1 wherein the yieldable means within the head for urging the yoke towards the plane of the handle comprises a coiled spring having inner and outer convolutions extending around the shaft carried by the yoke and disposed in the head, the inner convolution of said coiled spring being anchored to the

shaft, a rotatably adjustable sleeve within the head, the outer convolution of said spring being anchored to said sleeve.

3. A device as set forth in claim 1 including means whereby the handle may be adjusted and locked at various angular positions in a vertical plane in relation to the head.

4. A device as set forth in claim 1 wherein the means for maintaining the yoke in the plane of the axis of the handle comprises a torsional coil spring within the head and means for adjusting the force of said spring.

5. A device as set forth in claim 1 including spaced bearings within the head for the yoke carried shaft, spaced bearings in said head in which said shaft is rotatably mounted, a rotatable adjustable sleeve within the head between the bearings, a coiled torsional spring surrounding the shaft carried by the yoke within the adjustable sleeve, one end of said spring being anchored to the yoke carried member and the other end to the rotatable adjustable sleeve.

6. A device as set forth in claim 1 including a rotatably adjustable diamond ferrule carrying plug transversely of the carriage and a diamond ferrule extending transversely through said plug.

GEORGE A. PHILIPPE.
